UNITED STATES PATENT OFFICE.

WARREN L. LEE, OF CAMDEN, NEW JERSEY.

HAND-GUARD FOR LINEMEN, &c.

SPECIFICATION forming part of Letters Patent No. 690,302, dated December 31, 1901.

Application filed September 28, 1901. Serial No. 76,849. (No model.)

To all whom it may concern:

Be it known that I, WARREN L. LEE, a citizen of the United States, residing in the city and county of Camden, State of New Jersey, 5 have invented a new and useful Improvement in Hand-Guards for Linemen, Sailors, and others in Climbing and Descending, of which the following is a specification.

My invention consists of a guard for line-
men, sailors, and others in climbing and de-
scending electrical and other wooden poles,
masts, staffs, &c., the same being adapted to
be worn on the hand, and thus nicely under
control, provision being also made for exert-
ing greater power on the guard, rendering the
same most effective as it takes hold on said
poles.

Figure 1 represents a perspective view of
a guard embodying my invention. Fig. 2 rep-
resents an elevation taken from the back
thereof. Fig. 3 represents a face view thereof.

Similar letters of reference indicate corre-
sponding parts in the figures.

In the drawings, A designates a plate hav-
ing its working face B curved to conform to
a pole, mast, &c., to which it is to be pre-
sented, and studs or spurs C thereon. On
the back of the plate are ears D, through which
is passed the strap E, which is provided with
a suitable buckle F, whereby the plate may
be securely fastened to the hand of the user,
it being seen that when the article is in use
the plate is pressed against the pole, &c., and
the spurs or studs may take firm hold of the
same both in ascending or climbing and de-
scending, rendering the work easy and pre-
venting slipping, the guard being fully un-
der control of the hand, adapted to be con-
veniently manipulated, and is effective in op-
eration, while the thumb engages with the
adjacent portion of the strap, thus rendering
the plate fully controllable on the hand. The
back of the plate is also curved, preferably
similar to the face B, whereby the hand when

pressing against the same properly assumes 45
a curve shape thereon and rests comfortable
in position. The ears D are set eccentric or
at one side of the center of the plate, by which
provision a longer space is afforded for the
contact of the fingers, whereby the latter ob- 50
tain a greater purchase and leverage on the
plate, and thus assisted by the action of the
opposite wrist portion of the palm increased
power may be exerted on the device to press
it more firmly against the pole, &c., the effect 55
of which is evident. It will also be seen that
the hand is prevented from contacting with
the pole, &c., and so guarded from any in-
jury that might be occasioned by the same.

Having thus described my invention, what 60
I claim as new, and desire to secure by Letters
Patent, is—

1. A guard for the purpose described con-
sisting of a plate having a working face, a
spur on said face, and means on the plate for 65
attaching the same to the hand of the user,
said working face being primarily curved to
conform to a pole, mast, &c., to which it is
presented.

2. A plate having a curved working face, 70
a stud on the face thereof, ears on the back
of said plate, and a buckled strap engaging
said ears and being adapted to be passed
around the back of the hand of the user from
side to side of said plate, said parts being com- 75
bined forming a guard applicable to the hand
for climbing and descending a pole, &c.

3. A guard for the purpose described con-
sisting of a plate, a spur on the face of said
plate, and a strap for attaching said plate to 80
the hand of the user, said strap being con-
nected with said plate at a side of the center
thereof, said plate having a curved working
face.

WARREN L. LEE.
